UNITED STATES PATENT OFFICE.

STEPHEN O. TRECOTT, OF BATTLE MOUNTAIN, NEVADA.

AEROPLANE.

Application filed March 12, 1923. Serial No. 624,608.

To all whom it may concern:

Be it known that I, STEPHEN O. TRECOTT, a citizen of the United States, residing at Battle Mountain, in the county of Lander and State of Nevada, have invented certain new and useful Improvements in Aeroplanes, of which the following is a specification.

This invention relates to aeroplanes and 10 more particularly to the controlling means therefor.

An important object is to provide an aeroplane having means whereby the wings may be inclined transversely so as to enable 15 the aeroplane to rise rapidly or to enable the aeroplane to be successfully manipulated when in a nose dive.

A further object is to provide novel means whereby the propeller shaft and consequently the propeller may be swung about a horizontal axis or an axis extending transversely of the fuselage of the aeroplane so as to increase the ability of the plane to rise rapidly.

25 A further object is to provide an aeroplane which is of highly simplified construction, simple to control and cheap to manufacture.

In the accompanying drawings forming 30 a part of this application and in which like numerals are employed to designate like parts throughout the same.

Figure 1 is a fragmentary side elevation of the aeroplane, the planes being inclined transversely.

35 Figure 2 is a similar view, the wings being shown in their normal or horizontal positions.

Figure 3 is a fragmentary plan view of the improved aeroplane.

40 In the drawings wherein for the purpose of illustration is shown a preferred embodiment of the invention, the numeral 5 designates a body having its rear end formed with the usual control members 6 and 7 45 which form no part of this invention.

The oppositely arranged planes which are designated by the numeral 8 consist of upper and lower wings 9 and 10 respectively which are connected by struts 11.

50 The inner ends of the planes 8, which, as illustrated in Figure 3, are arranged at opposite sides of the body are provided with disks 14 arranged in opposed relation to disks 15 carried by the body. Ball bearings 55 16 or other suitable anti-friction elements are confined between the disks 14 and 15 and

permit the planes to be rotated about an axis extending transversely of the body.

A shaft 20 is extended transversely through the body and terminates beyond the ends of the planes and has its ends formed with cross members or rods 21 which are connected to the body by means of bracing wires 22. Anti-friction elements 23 are located at the connection between the shaft 60 20 and the cross rods 21 and permit the shaft to be easily rotated. However, the shaft has rigid connection with the planes, so that when the shaft is rotated the planes also will be rotated.

70 The shaft 20 may be manually rotated for positioning the planes by means of the lever 30 having a dog 31 adapted to be engaged with the teeth of a ratchet wheel 32 mounted on the shaft. The lever 30 is also 75 mounted on the shaft and when it is operated the ratchet wheel 32 and consequently the shaft is rotated for tilting the plane.

The ratchet wheel 32 is also engaged by a second lever 34 having its rear end formed 80 with a weight or spring 36. The weighted lever 34 co-operates with the lever 30 in holding the ratchet wheel in an adjusted position.

It is thus seen that the planes may be 85 manually tilted by the operator so as to properly present the planes to the wind. This permits the operator to exercise greater control over the aeroplane and consequently 90 renders flying much safer than at present.

95 The propeller shaft 38 may be tilted about an axis extending transversely of the vehicle for varying the position of the propeller 39. As illustrated in figure 3, the propeller shaft 38 is movable through a slot 40 in the top of the body and a collar 41 is mounted on the shaft 38 and has connection with the forward end of a lever 44. The lever 44 is pivoted intermediate its ends as indicated at 46 and has its rear end formed 100 with a handle 49 which is arranged within convenient reach of the operator. A dog is arranged on the lever 44 and is engaged with a rack or segment 52 arranged within the body and the said dog and the segment 105 form a convenient means for holding the lever in a set position. Any suitable means such as a bevel gear connection, a friction wheel and disk connection, may be employed for connecting the propeller shaft to the 110 engine. If desired, a flexible shaft may be employed.

With reference to the foregoing description taken in connection with the accompanying drawing it will be seen that an aeroplane constructed in accordance with 5 this invention may ascend very rapidly. It may also descend very rapidly. In case the machine gets in the nose dive it may be manipulated very successfully by tilting the planes transversely by means of the im- 10 proved mechanism.

I claim:-

1. An aeroplane comprising a body, a shaft extending through the body, planes mounted on the shaft at opposite ends of 15 the body, a rod arranged at each end of the shaft and having a rotatable connection therewith, connecting wires joining each rod with the body, a lever connected to the shaft and forming a means whereby the 20 planes may be inclined transversely, a ratchet wheel mounted on said shaft, and a dog carried by said lever and adapted to engage said ratchet wheel.

2. The construction set forth in claim 1,

and a second lever engaged with said wheel 25 and having one end formed with a weight.

3. The construction set forth in claim 1, a propeller shaft, said body being provided with a slot receiving said shaft, and a lever having a collar connected to said propeller 30 shaft.

4. The combination with the body of an aeroplane, of a transverse rotatable shaft, planes mounted on said rotatable shaft, a gear for rotating the said shaft and planes, 35 a lever having dogs to engage said gear, a propeller shaft having a propeller affixed thereto, a slot in the fuselage of the aeroplane permitting oscillation of the propeller shaft, and a bell-crank lever for oscillating 40 the said propeller shaft and propeller.

In testimony whereof, I have affixed my signature in the presence of two witnesses.

STEPHEN O. TRESCOTT.
